UNITED STATES PATENT OFFICE.

JOHN F. O'CONNOR, OF CHICAGO, ILLINOIS, ASSIGNOR TO WILLIAM H. MINER, OF CHAZY, NEW YORK.

DRAFT-RIGGING FOR RAILWAY-CARS.

1,369,536.

Specification of Letters Patent. Patented Feb. 22, 1921.

Application filed July 5, 1919. Serial No. 308,830.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railroad cars.

The object of my invention is to provide an efficient friction spring draft gear for railroad cars.

In the drawings forming a part of this specification, Figure 1 is a horizontal sectional view partly in top plan of a draft rigging, embodying my invention. Fig. 2 is a cross-section taken on line 2—2 of Fig. 1. Fig. 3 is a central vertical longitudinal section of the rear portion of the shell employed in the construction shown. Fig. 4 is a perspective view of the spring case compressing member. Fig. 5 is a perspective view of one of the spring cases employed.

Referring to the drawings, the draft members, in this instance the center sills 10, are provided upon their inner faces with the front stops 11 and the rear stops 12. The draw bar 13 of which only the rear portion is shown, is mounted between the draft member having attached thereto a draft yoke 14 of the usual construction and adapted to inclose within it the draft gear embodying my invention. A front follower 15 is also mounted within the yoke, the function of the rear follower being performed by the rear end 16 of the shell 17. The shell 17 comprises a longitudinally arranged hollow member 18, and an integral hollow member 19 transversely arranged and open at both its ends. The whole shell is in general conformation a hollow T-shaped member. Within the longitudinally extending portion of the shell is mounted the friction shoes 20 provided with a centrally arranged wedge member 21, which engages the front follower 15 and within the shell engaging the friction shoes are the springs 22 comprising an outer coil and an inner coil, the latter being seated against the washer 23, engaging the shoulders 24 of the shoes.

At the rear end, the said springs are

seated against the forward face 124 of a spring case compressing member 25 which is provided as at 26 with a longitudinally extending stem adapted to be engaged by the friction elements hereinbefore described when the same shall have traveled inwardly sufficiently to engage the end thereof. The member 25 is a block-like element provided with a pair of inwardly converging inclined planes 27—27 whose function is hereinafter described and which enter the transverse hollow portion of the shell. Oppositely arranged therefrom in said transverse hollow portion is a further block-like member 28, similarly provided with inwardly extending inclined planes 29—29 which are adapted to coöperate with the member 25 in drawing the spring cases hereinafter described toward each other. The said spring cases each comprise a hollow member 31, closed at its outer end 32 and open at its inner end, each being provided at its inner end with a pair of upper and lower planes 33 and 34 respectively, each pair consisting of the converging planes 34—34. The forward planes 34 are adapted to be engaged by the surfaces 27 of the spring case compressing member 25 and the rear planes 34 are adapted to be engaged by the surfaces 29—29 of the member 28. Mounted within the spring cases and extending between the same is a spring element 35, consisting preferably of the outer coiled spring 36 and the inner coiled spring 37. In normal position of the parts as illustrated in Fig. 1 of the drawing, the two spring cases are spaced apart at their inner open ends, their outer ends being adjacent the draft members 10. The member 28 and the spring case compressing member 25 are provided adjacent the spring cases with the hollowed out portions 38 to permit their travel toward each other without being impeded by the spring cases 31.

Further described, the spring case compressing member 25 and its opposed member 28 are each provided with a wedge-shaped recess, vertically arranged within which the wedge-like members upon the inner ends of the spring cases are received and are also provided with transverse recesses to permit their longitudinal movement in reference to the shell. The parts between the draft members are supported by the tie plate 39. The spring case compressing member 110

and its opposed member 28 from the foregoing description will be observed to have engaging faces which from the description of the device hereinafter following will be seen to be frictional faces, the same being the inclined planes 27 on the spring case compressing member, the similar inclined planes 29 upon an opposed member 28 and the inclined planes 34—34 front upon the wedge-like member of the spring cases.

In rearward movement of the draw-bar, the wedge member 21 and the shoes 20 of the friction elements in the front portion of the shell move rearwardly, being resisted by the springs 22 which are held by the spring case compressing member 25 until the rearward pressure of the springs 22 is greater than the resisting pressure of the transverse spring within the spring cases plus the frictional resistance generated in connection therewith. In preferable construction, the compression resisting power of the elements within the transverse portion of the shell is greater than that of those within the longitudinal portion of the shell. In such arrangement after a preliminary movement of the longitudinal springs 22, the friction elements in the longitudinal opening of the shell will engage against the stem 26, and upon the movement of the spring case compressing member 25 rearwardly, the spring cases 31 are by reason of their engagement between the front compressing member 25 and rear compressing member 28, drawn or squeezed toward each other against the resistance of the contained spring, this movement being also resisted by the friction between the compressing elements 25 and 28 and the wedge-like members upon the spring cases. The spring cases may be so spaced apart and the wedge-like openings in the members 25 and 28 forming the planes 27—27 and 29—29 thereon respectively so connected that upon full compression of the springs 36 and 37 the open ends of the spring cases will engage each other to prevent over-compression of the springs. On forward movement of the draw-bar, the wedge member 21 remains stationary against the front follower 15, the shell is drawn forwardly by the yoke and the action of the various parts within the shell is the same as upon rearward movement of the draw-bar hereinbefore described.

55 I claim:

1. In a friction shock absorbing mechanism, the combination with a friction shell; of friction elements coöperable with said shell; spring means for yieldingly resisting relative movement between said shell and friction elements; an abutment, movable with respect to the shell, for the end of the spring means remote from the friction elements; and combined friction and spring means for yieldingly resisting relative

movement between said abutment and said shell, said combined friction and spring means including friction elements movable transversely of said friction shell.

2. In a friction shock absorbing mechanism, the combination with a casting having a longitudinally extending spring chamber and a transversely extending chamber in communication with one end of said spring chamber, the casting being provided with interior friction surfaces at the opposite end of said spring chamber; of friction elements coöperable with said friction surfaces; spring means within said spring chamber and compressible in a direction parallel to the axis thereof; and combined friction and spring devices in said transverse chamber including, an element forming a yieldable abutment for the inner end of said spring means.

3. In a friction shock absorbing mechanism, the combination with a friction shell; of friction elements coöperable with said shell; spring means for yieldingly resisting relative movement between said shell and friction elements; an abutment, movable with respect to the shell, for the end of the spring means remote from the friction elements; combined friction and spring means for yieldingly resisting relative movement between said abutment and said shell, said combined friction and spring means including friction elements movable transversely of said friction shell; and a pressure-transmitting column interposed between said friction elements and said abutment and of a lesser length than the normal distance therebetween, said column being adapted, after a predetermined movement of the friction elements relatively to the shell, to transmit pressure directly between the friction elements and said abutment.

4. In a friction shock absorbing mechanism, the combination with a friction shell having a spring chamber therein; of friction elements coöperable with said shell; spring means within said chamber adapted to yieldingly resist relative movement between the friction elements and the shell; an abutment for said spring means at the end of the spring chamber remote from the friction elements, said abutment being movable relatively to the shell; transversely compressible spring means on the opposite side of said abutment from that of the first named spring means and friction wedge elements arranged to be actuated by said abutment for compressing the said transversely compressible spring means.

5. In a friction shock absorbing mechanism, the combination with a casting having a longitudinally extending chamber at one end and a transversely extending chamber at its other end, the two chambers being in communication with each other, said casting having interior friction surfaces at the outer

end of the first named chamber; of friction elements coöperable with said surfaces; a longitudinally arranged spring within said longitudinally extending chamber; a trans-
versely arranged spring within the trans-
versely extending chamber; spring caps for
said transversely arranged spring, said caps
having friction wedge faces; and oppositely
disposed wedging members coöperable with

said wedge friction faces of the spring caps, 10
one of said members providing a yielding
abutment for the inner end of said longitudi-
nally arranged spring.

In witness that I claim the foregoing I
have hereunto subscribed my name this 14th 15
day of June, 1919.

JOHN F. O'CONNOR.
